UNITED STATES PATENT OFFICE.

EDGAR M. HAWKINS, OF ROCHESTER, NEW YORK, ASSIGNOR TO M. D. KNOWLTON COMPANY, OF ROCHESTER, NEW YORK, A CORPORATION OF NEW YORK.

MACHINE FOR MAKING CORRUGATED PAPER-BOARD.

1,327,158.

Specification of Letters Patent.

Patented Jan. 6, 1920.

Application filed April 24, 1918. Serial No. 230,413.

To all whom it may concern:

Be it known that I, EDGAR M. HAWKINS, a citizen of the United States, and resident of Rochester, in the county of Monroe and State of New York, have invented certain new and useful Improvements in Machines for Making Corrugated Paper-Board, of which the following is a specification.

10 This invention relates to machines for making lined corrugated board, such, for example, as disclosed in my pending application, Serial No. 69,093.

15 The machine of that application comprises a pair of corrugating rolls which corrugate the filler and transfer it to a rotary drum having corrugations adapted to receive and hold the corrugations formed on the filler. While the corrugated filler 20 is being so carried on the surface of the drum, it has applied thereto a coat of adhesive by means of an adhesive-applying device capable of applying the adhesive to the ridges of the corrugations. The corrugated filler with its coat of adhesive then 25 has applied thereto a liner or facing which is suitably conducted to the periphery of the drum. The corrugated filler, then provided with one liner, travels with the drum 30 for a predetermined distance and is removed therefrom by a transfer roll in such manner as to expose the unlined side of the corrugated filler. Adhesive is then applied to the ridges of the corrugations on the unlined side of the filler after which the other 35 or second liner is applied. The filler then lined on both sides is passed over a heating bed to dry the adhesive and firmly unite the layers.

40 The arrangement of parts in that machine, however, is such that the lined filler is passed over the heating bed with the last formed joint, that is, the joint between the filler and the last-applied liner, separated 45 from the heating bed by both the corrugated filler and the lower or first-applied liner. This of course does not result in as quick setting of said last formed joint as would result if that joint were next the heating bed 50 when the lined filler is passed thereover, and as it is desirable that the joint should be set as quickly as possible, it has been one of the objects of my present invention to provide for the accomplishment of this, 55 which is done in the present case by locating

the heating bed at the upper side of the path of the lined board and next to the last formed joint.

In the former construction, wherein the lined filler passed over the heating bed, said 60 lined filler, in the event of the machine being stopped for any reason, was liable to become burned. In the present case, where the heating bed is above the lined filler, I am enabled to avoid the possibility of such 65 burning by the provision of means for effecting the quick lowering of the support over which the lined filler passes, whereby, upon the stopping of the machine, said support may be lowered and thereby permit of 70 the lined filler sagging or dropping away from contact with the heating bed. For the ready and convenient manipulation of said support manually operable raising and lowering means therefor are preferably em- 75 ployed.

In addition to the above mentioned features, there are other novel features which will appear as the specification proceeds.

The invention is illustrated in its preferred form in the accompanying drawings, in which—

Figure 1, is a more or less diagrammatic side elevation of the machine showing the general arrangement of the various parts 85 thereof and the paths of travel taken by the filler and the two liners;

Fig. 2, is a top plan of the same;

Fig. 3, is an enlarged central longitudinal and vertical section through the main front 90 end of the machine which is that part embodying my present invention;

Fig. 4, is a vertical cross section taken on the line 4—4 of Fig. 3;

Fig. 5, is detail plan showing part of the 95 connection between the supporting bed for the lined filler and its raising and lowering mechanism;

Fig. 6, is an enlarged detail, partly in section, of part of the operating means for 100 raising and lowering said bed;

Fig. 7, is an enlarged detail showing one of the brush holders and the connection of the same with its associated parts.

Referring to the drawings, particularly to 105 Figs. 1 and 3, it will be seen that the filler α of straw board or other suitable material to be corrugated and subsequently lined, is fed from a roll α' to the corrugating rolls, denoted generally by the reference character 110

A. The filler is corrugated by means of these rolls and then transferred to the corrugated heating drum B, which carries the corrugated filler to a transfer roll C by means of which the corrugated filler is removed from the drum.

Just after the corrugated filler has been gripped by the drum B, the adhesive-applying mechanism, denoted generally by the 10 reference character D, applies adhesive to the ridges of the corrugations. The corrugated board so coated with the adhesive then has applied thereto the bottom liner b which is conducted to the periphery of the drum B 15 from a supply roll b' over a preheating device, denoted generally by the reference character E. The bottom liner so brought into contact with the adhesive coated corrugated filler, adheres thereto and is carried with the corrugated filler to the transfer roll C where the filler, lined on one side, is removed from the drum and reversed so that the unlined side of the corrugated filler is exposed to the adhesive-applying mechanism 25 nism, indicated at F. In this manner, the ridges of the corrugations on the unlined side of the filler have applied thereto a coating of adhesive so that the second or top liner will adhere thereto. This second liner 30 c is fed from a supply roll c' over a preheating device G similar to the preheating device E for the bottom liner. A pressure roller H brings the top liner into proper relation with the adhesive coated corrugations 35 of the filler, thus causing the top liner to adhere to the corrugated filler. A set of pull rolls I, between which the completed material passes, draws the lined corrugated filler past a heating bed, denoted generally 40 by J, against which it is yieldingly held by a supporting bed, J'.

The above description gives a broad idea of the general arrangement and operation of the main parts of the machine, and the 45 following description will set forth more in detail the construction of certain of those parts.

The drum B is rotatably mounted in the main standards 1 and 2 of the machine (Fig. 50 4), and is provided over its entire surface with a plurality of corrugations running longitudinally of the drum. The corrugating mechanism A for corrugating the filler and from which the filler is transferred to 55 said drum B, comprises a pair of corrugating rolls 4 and 5, each provided over its entire surface with teeth or corrugations running longitudinally of the rolls. The teeth of these two rolls mesh so that the filler passing between them is corrugated in well known manner. The teeth of the roll 4 also mesh with the teeth on the drum B, so that the corrugations of the filler board are directly positioned in the corrugations on the 60 drum B when transferred to the latter. The

teeth on the drum B cause the corrugated filler to move with the drum and maintain the spacing of the corrugations in the filler until secured by the liner to be adhesively applied thereto.

70

The mechanism D for applying adhesive to the corrugated filler comprises an adhesive-containing pan or trough 21, with which are associated an adhesive-applying roll 29 and an adhesive-distributing roll 31, the latter taking the adhesive from the pan 21 and distributing it onto the roll 29, and the latter in turn applying the adhesive to the ridges of the corrugations of the filler on the drum B.

75

The bottom liner b is carried from its supply roll under a guide roll 55, then up over the periphery of the heating pipe E, then downwardly under a pressure roll 56, and from thence upwardly to a roll 46 just below the adhesive-applying mechanism D, over which it passes into contact with the adhesive coated filler on the surface of the drum.

80

The corrugated filler, now supplied with the bottom liner, is carried with the drum until the transfer roll C is reached. The corrugated filler and bottom liner then pass around this transfer roll with the bottom liner adjacent to the surface of the roll. 90 The unlined side of the filler is therefore exposed in passing around the transfer roll C, thus giving an opportunity of applying adhesive to the corrugations at the unlined side of the filler. This is done by means of the 95 adhesive-applying mechanism F, which is similar in all respects to the adhesive-applying mechanism D for applying adhesive to the opposite side of the filler.

95

The top liner c is applied to the corrugated filler as the latter reaches the upper part of the transfer roll C. The top liner is conducted to this point from the supply roll c', over an idler roll 79, to and under an adjustable tension roll 80, and from thence over 110 the periphery of the preheating device G, from which it passes under a pressure roll 81 to the filler on the transfer roll C.

105

The construction and operation of the machine as thus far described, except the supporting and heating beds J and J' hereinbefore briefly referred to, is substantially the same as that of the machine of my aforesaid pending application and therefore does not here require further detailed description. 120

115

The corrugated filler, now lined on both sides as described, passes from the transfer roll C between the supporting bed J' and the heating bed J. The heating bed J comprises several horizontally aligned steam chests 100 which are supported from the upper frame-work 101 by suitable fastening means, such as the bolts 102. Steam may be supplied to these chests in any usual or suitable manner.

130

The supporting bed J' above referred to comprises a frame carrying a plurality of pressure devices, here shown in the form of upstanding brushes, which act to yieldingly but firmly hold the lined filler up against the heating bed as it is drawn thereover by the pull rolls I. In this manner, the lined filler is brought into intimate contact with the heating bed with the last formed joint, that is, the one between the filler and the upper liner, in position next to said heating bed, whereby a quick setting of said joint will be effected.

The frame of this bed J' comprises longitudinal side members 105 and connecting cross members 106, both in the form of angle irons as shown. Extending transversely across this frame are a series of bars 107 carrying brushes 108 and mounted at their ends in holding brackets 109 which are detachably connected to the side members 105 by suitable fastening means, such as the clamping screws 110 (see Figs. 4 and 7). It will be noted that the brushes are set to have a rearward inclination so that the lined filler will slide freely over them when being drawn through the machine. At the front end of this brush carrying frame is a transverse bar 111 to which is secured a sheet of canvas or other flexible material 112 passing rearwardly over the tops of the brushes. This canvas, intervening between the brushes and the lined filler, serves to more evenly distribute the pressure of the brushes against the surface of the lined filler in the passage of the latter thereover.

The supporting bed just described is supported vertically by a plurality of coiled springs 114, here shown as four in number and arranged with two at each side of the frame. These springs are interposed between the under side of the cross members 106 of the frame and stationary brackets 115 on the main framework, and are positioned about guide spindles 116 which are carried by the brackets 115 with their upper ends extending freely through openings in the frame members 106. In this way the supporting bed may be easily raised and lowered with respect to the heating bed, as it is substantially balanced by the springs 114, and it will be guided in its vertical movements by the guide spindles 116.

As a means for raising and lowering the supporting bed J' with respect to the heating bed, I provide two rock shafts 117 which extend transversely of the machine below said supporting bed and are journaled in suitable bearings 118 on the frame work. These rock shafts are provided adjacent their opposite ends with short crank arms 119 which connect through the medium of pivoted links 120 with the opposite sides of the supporting bed, whereby, upon the rocking of the shafts, a raising and lowering of

the connected bed will be effected. In order that the shafts may be caused to move in unison and thereby cause a uniform raising and lowering of the bed throughout its length, they are provided with a second set 70 of crank arms, 121, connected by a rod 122.

A lever 123 secured to one of said rock shafts serves as a means to operate the bed raising and lowering mechanism, this lever as here shown being formed with an opening 75 124 near its handle end to receive there-through a latch bar 125 which is pivoted at its lower end to a stationary bracket 126 secured on the floor or other support. A latch connection between the lever and this bar is 80 made by means of a latch pin 127 which is carried by the lever and adapted to engage the bar at different points in the length thereof through openings 128 therein (see Figs. 1 and 6), the said pin being operated 85 to engage and disengage the bar 125 by means of a connecting lever-handle 129 which is pivoted to the lever 123 at 130 and serves as a handle for said lever. The arrangement of this lever handle is such that 90 the operator, grasping the same, may operate it to first disengage the pin 127 from the bar 125, and then, while still grasping the handle, swing the lever 123 in a direction to effect the desired raising or lowering of the 95 supporting bed J', after which the handle may be operated to cause the latch pin to re-engage the bar 125 and hold the bed stationary in its adjusted position.

As hereinbefore stated, one of the primary reasons for having the bed J' capable of a raising or lowering movement with respect to the heating bed, is for the purpose of enabling the operator to quickly lower the bed when the machine is stopped to permit the supported paperboard dropping or sagging away from the heating bed and thereby prevent it from becoming burned. It will be clear that this may be readily and conveniently accomplished by the construction illustrated and described.

Although my present invention has been set forth in its preferred form, it is obvious that numerous modifications and changes may be made in the details of construction, without departing from the spirit or scope of the invention as defined in the accompanying claims.

What I claim is:—

1. The combination with mechanism for lining a web of paper and the like, of a heating bed beneath which the lined web passes, and a supporting bed arranged beneath the heating bed for holding the lined web to said heating bed and being vertically 120 adjustable with respect to the latter, for the purpose described.

2. The combination with mechanism for lining a web of paper and the like, of a heating bed beneath which the lined web passes, 130

- and a supporting bed arranged beneath the heating bed having means for yieldingly holding the lined web to said heating bed and being vertically adjustable with respect to the latter, for the purpose described.
3. The combination with mechanism for lining a web of paper and the like, of a heating bed beneath which the lined web passes, and a supporting bed having a flexible surface for engaging the under side of the lined web and holding it to the heating bed, said supporting bed being vertically adjustable with respect to the heating bed, for the purpose described.
4. The combination with mechanism for lining a web of paper and the like, of a heating bed beneath which the lined web passes, and a supporting bed for holding the lined web to said heating bed and being vertically adjustable with respect to the latter, said supporting bed comprising a plurality of yielding pressure devices, for the purpose described.
5. The combination with mechanism for lining a web of paper and the like, of a heating bed beneath which the lined web passes, and a supporting bed for holding the lined web to said heating bed and being vertically adjustable with respect to the latter, said supporting bed comprising a plurality of yielding pressure devices and a strip of flexible material resting thereon, for the purpose described.
6. The combination with mechanism for lining a web of paper and the like, of a heating bed beneath which the lined web passes, a supporting bed arranged beneath the heating bed for holding the lined web to said heating bed, and means for raising and lowering the supporting bed with respect to the heating bed.
7. The combination with mechanism for lining a web of paper and the like, of a heating bed beneath which the lined web passes, a balanced supporting bed arranged beneath the heating bed for holding the lined web to said heating bed, and manually operable means for quickly raising and lowering the supporting bed with respect to the heating bed.
8. The combination with mechanism for lining a web of paper and the like, of a

heating bed beneath which the lined web passes, a spring-balanced supporting bed for holding the lined web to said heating bed, and manually operable means for quickly raising and lowering the supporting bed with respect to the heating bed.

9. In a machine for lining webs of paper and the like, the combination of means for applying adhesive to said web, means for applying a liner to the adhesive-coated side of said web, a heating bed, supporting means arranged beneath the heating bed and engaging the under side of the lined web and holding it with the liner in contact with the heating bed, and manually operable means for raising and lowering said supporting means with respect to the heating bed.

10. In a machine for lining webs of paper and the like, the combination of means for applying adhesive to said web, means for applying a liner to the adhesive-coated side of said web, a heating bed, yielding supporting means arranged beneath the heating bed and engaging the under side of the lined web and holding it with the liner in contact with the heating bed, and manually operable means for raising and lowering said supporting means with respect to the heating bed.

11. In a machine for lining webs of paper and the like, the combination of means for applying adhesive to one side of said web, means for applying a liner to the adhesive-coated side of said web, means for applying adhesive to the opposite side of said web, means for applying a liner to the last coated side of said web, a heating bed, means for directing the lined web beneath the heating bed with the last applied liner next said heating bed, unheated supporting means engaging the under side of the lined web and holding it to said heating bed, and means for raising and lowering said supporting means with respect to the heating bed.

Signed at Rochester, in the county of Monroe, and State of New York, this 17th day of April, A. D. 1918.

EDGAR M. HAWKINS.
